UNITED STATES PATENT OFFICE.

SAMUEL BABCOCK, OF MIDDLETON, CONNECTICUT.

IMPROVED SNAP-HOOK.

Specification forming part of Letters Patent No. 40,806, dated December 8, 1863.

To all whom it may concern:

Be it known that I, SAMUEL BABCOCK, a resident of Middletown, in the county of Middlesex and State of Connecticut, have invented an Improved Snap-Hook or Mousing-Hook; and I do hereby declare the same to be fully described in the following specification and represented in the accompanying drawings, of which—

Figure 1 is a side elevation; Fig. 2, a rear view, and Fig. 3 a longitudinal section of it. Fig. 4 is a perspective view of its hook and eye as separated from the movable tongue. Fig. 5 is an inner edge view, and Fig. 6 is a longitudinal section of the tongue as separated from the hook.

The nature of my invention consists in an improved manufacture of snap-hook or mousing-hook, as made not only with its eye in one piece with its hook, and with its tongue not only provided with lips to embrace the shank of the hook and form a joint therewith, but with a recess arranged substantially as described, and for the purpose of carrying a straight or leaf spring disposed within such recess in the manner as hereinafter specified.

In the drawings, *a* denotes the eye, while *b* is the hook, they being cast or forged in one piece of metal. The tongue is represented at *c* as formed with a long recess, *d*, extending nearly through it longitudinally. It also has two circular lips, *e e*, arranged at its upper end, and so as to embrace the upper part, *f*, of the shank of the hook *b*, and form therewith a joint through which a joint-pin, *g*, is to pass and connect the tongue to the hook.

Within the recess *d* of the tongue there is a leaf-spring, *h*, which at or near its lower end is fastened to the tongue by a nut, *i*, while at its upper end it bears against a projection, *k*, formed on the shank of the hook, as shown in the drawings. This spring serves to press the tongue close up to the extremity or part *l* of the hook.

I am aware of the snap and mousing hooks described or set forth in the United States Patents numbered 21,879 and 30,084, and therefore I do not claim them or the peculiar arrangement of their parts. In the first one—viz, that numbered 21,879—although the hook and eye are in one piece, the lips are formed

on the hook and not on the tongue, as in my improvement; and, furthermore, the hook and tongue are formed to receive a spiral spring, whereas the tongue only of my hook is recessed to receive a leaf-spring. The objection to the spiral spring is that, after being in use it is liable to lose its elasticity and become set, so as to impair the correct operation of the tongue; and, furthermore, the recessing or cutting away of the shank of the hook in order to receive the spring greatly weakens the shank and renders it liable to break off under a severe strain. In my invention the shank is not recessed to receive the spring, and therefore its strength is not impaired by any such recess.

In the snap-hook shown in Patent No. 30,084 the eye is formed in one piece with the tongue, and consequently the strain on the hook is borne by the joint-pin of the eye. This renders such joint-pin, although provided with lips, liable to soon work loose or break.

My improved snap-hook, owing to its peculiar construction, is very strong and little liable to become broken under great strain while in use. Furthermore the hook and the eye can be cast or founded in one piece, without the necessity of subsequently twisting the shank of the hook, as becomes necessary when the lips are formed on the upper part of the hook itself, in which case, in order to draw the pattern from the mold, it has to be formed with the point of its hook arranged askew relatively to the shank, the parts after having been cast requiring to have the shank twisted to bring them into correct positions. This twisting of the shank weakens it and renders it liable to break when the hook may be in use.

I am aware of the snap-hooks described in the Letters Patent respectively numbered 35,931, 39,659, and 39,670. I do not claim either of them, or their modes of construction, as embodying my invention, which is as much an improvement on the ordinary snap-hook as is either of the others to which I have alluded, and besides causes my improved snap-hook to possess advantages not incident to either of the others.

I claim as my invention—

The improved manufacture of snap-hook as made, not only with its eye in one piece with its hook, and with its tongue not only provided with lips to embrace the shank of the hook and form a joint therewith, but with a recess arranged substantially as described, and the purpose of carrying a straight or leaf

spring disposed within such recess, in manner as hereinbefore explained.

SAML. BABCOCK.
